UNITED STATES PATENT OFFICE.

CHARLES SCHAUUMBURG, OF PARK RIDGE, ILLINOIS.

DESIGN FOR A STRAINER-HOLDER.

58,112.

Specification for Design.

Patented June 7, 1921.

Application filed March 29, 1919. Serial No. 286,175. Term of patent 7 years.

To all whom it may concern:

Be it known that I, CHARLES SCHAUUMBURG, a citizen of the United States, residing at Park Ridge, in the county of Cook and State of Illinois, have invented a new, original, and ornamental Design for Strainer-Holders, of which the following is a specification, reference being had to the accompanying drawing, forming a part of this application.

The drawing shows a perspective view of the strainer holder with the strainer indicated in dotted lines in position to be inserted in the holder.

What I claim and desire to secure by Letters Patent is:

An ornamental design for a strainer holder as shown.

CHARLES SCHAUUMBURG.
